UNITED STATES PATENT OFFICE.

CHESTER M. BALDWIN, OF BRONSON, MICHIGAN, ASSIGNOR OF THREE-FOURTHS TO SAMUEL HOLMES, MARY E. BISSELL, AND CHARLES H. WARREN, ALL OF SAME PLACE.

CAR-COUPING.

SPECIFICATION forming part of Letters Patent No. 336,466, dated February 16, 1886.

Application filed August 10, 1885. Serial No. 174,055. (No model.)

To all whom it may concern:

Be it known that I, CHESTER M. BALDWIN, a citizen of the United States, residing at Bronson, in the county of Branch and State 5 of Michigan, have invented a new and useful Improvement in Car-Couplings, of which the following is a specification.

My invention relates to coupling cars automatically by means of a hook working in a 10 slot through the draw-head. The hook is held down by a spring. The uncoupling is effected by a lever-rod across the end of the car, in the center of which is a loop, to which a chain is attached connecting with the hook. The 15 rod is bent round the sides of the car so as to form a lever at either side, to one of which is attached an upright rod reaching a little above the top of the car, being bent at the top so as to form a foot-rest by which the brakeman, by 20 a pressure of the foot, can uncouple from the top of the car.

The object of my improvements is not only the saving of time in handling trains on railroads, but also the lessening of danger to operators by obviating the necessity of going 25 between the cars to couple or uncouple. I attain these objects by the mechanism illustrated in the accompanying drawings, in which—

Figure 1 represents the end of a car to which 30 a draw-head is attached; also, a lever-rod across end of car, and an upright rod and chain from hook to lever-rod. Fig. 2 represents sectional view of draw-head, showing position of hook, spring, and link when in operation.

35 The several parts are referred to by letters. The draw-head A has cut through it a slot, B, into which is placed a hook, C, through which, opposite the hook end, passes a bolt, D. The point of the hook C rests on the convex 40 surface E in the bottom of the mouth of the draw-head A. The bolt D passes through the draw-head A and hook C, below the line of draft, thereby throwing a large percentage of draft onto point of hook C, relieving the bolt 45 D of much of the strain of draft, which makes a much stronger coupling than the pin and link now in general use. When making a coupling, the link passes into the mouth of the

draw-head, raising the hook C as it enters. When the link F has passed the point of the 50 hook C, the spring G instantly presses down the hook C, when the link F is secured and the coupling made as shown in Fig. 1 of drawings. The link F can be held in a horizontal position by pushing it into the mouth of the 55 draw-head A as far as possible, which position it will be placed in when coupling cars of the same height, or nearly so. When there is considerable difference in height, the link F will be placed in the higher draw-head and drawn 60 out as far as the point of the hook C will permit, which will allow the outer end of the link F to drop down at an angle of about thirty degrees, when the coupling can be made as stated above. 65

a a is the lever-rod across the end of the car; b b, the levers bent around the sides of the car; c, the upright rod bent at top to form a foot-rest, d; e, loop at center of lever-rod a a; f, chain fastened to loop e in rod a a and hook C immediately over the hook end. 70

To uncouple, the operator pulls down the lever b at side of car, which causes the chain f, attached to the loop e, to raise the hook C in the slot B, which releases the link F, allowing 75 it to pass out of the mouth of the draw-head A.

It will be seen that by pivoting the inner rear end of the hook C in the lower rear portion of the slot B at D, and forming the curved or convex block E on the lower inner side of 80 the mouth of the draw-head, upon and against which the point of the hook rests, and which serves to lift the operative end of the hook above the horizontal plane of the pivotal pin D of the same, as clearly shown in Fig. 2 of 85 the drawings, the pivot-bolt D is relieved of a great portion of the strain, the line of draft being by this arrangement thrown largely upon the operative end or upper outer portion of the hook C, and as the outer operative end 90 of the hook above the plane of the pivotal point rests and bears against the convex block E, the said block serves to sustain a portion of the draft or strain, this being especially the case where the link F is inclined downward 95 at its free outer end to enable it to enter the

mouth of a draw-head below the level of the one in which the link is at the time secured, which is frequently the case.

I am aware that in car-couplings as heretofore constructed a spring-actuated hook pivoted in a vertical slot in the draw-head, and provided with means for operating it from the top or sides of the car is old, and I do not therefore claim such construction broadly; but

10. What I claim as my invention, and desire to secure by Letters Patent of the United States, is—

As an improvement in car-couplings, the combination, with the draw-head having the vertical slot and formed with the convex block, arranged as described, of the spring-actuated hook pivotally secured in the lower rear part of the said slot below the line of draft, and

having its point resting against the said convex block above the line of draft, the trip-rod secured in bearings across the front of the car, provided with the central double-crank portion, and having its ends bent at right angles to form lever arms, the chain connecting the double crank of the said trip-rod to the upper front end of the hook in the draw-head, and the foot-rod pivoted at its lower end to one of the lever-arms of the top rod, and adapted to be operated by the foot of the operator from the top of the car, all constructed, combined, and arranged to operate in the manner and for the purpose herein shown and set forth.

CHESTER M. BALDWIN.
